QUICKPROOF PROCESS FILM

Luther G. Simjian, New Haven, Conn., assignor
to Neel Associates, Inc., New York, N. Y., a cor-
poration of New York

Application October 30, 1931, Serial No. 572,045

7 Claims. (Cl. 95—8)

This invention relates to improvements in quick proof process films having for an object to provide such a combination of elements, including different characters of sensitized emulsions, 5 one of which is very fast and will, upon being photographically exposed, developed and placed under a strong light-ray, produce a visible image upon the other emulsion without further subjecting the same to any kind of developing solution, and a further object of the invention is to 10 provide a novel means for combining such elements.

The Figure 1 is a cross-section of a substantially transparent base 1 having upon one side 2 a negative emulsion 3 and upon the side 5 a coating of printing-out emulsion 6 covered by a waterproofing 7; Figure 2 is a cross-section of a substantially transparent base 1' having on the side 2' negative material 3' and on the side 5' printing-out paper 6' covered by a waterproofing 7'; Figure 3 is a cross-section of negative material 3''' and printing-out paper 6''' with plastic layer 4''' between, the outer surface of printing-out paper 6''' having the waterproofing 7'''; Figure 4 is a cross-section of plastic base 1''' having on its outer side 2''' a negative emulsion 3''' and upon its side 5''' printing-out emulsion 6'''; Figure 5 is a perspective of negative material and printing-out paper marginally cemented, one to the other, one corner being turned down; and Figure 6 is an end view of negative material and printing-out paper physically distinct, one from the other.

It is apparently old in the art to provide films 35 comprising certain layers of structure, including a dissoluble coating removable by a hot bath before subjecting the positive to a developing solution, but the improvement about to be explained provides a film having a base between 40 layers of sensitized emulsion of such distinct characters that, upon a photographic exposure and developing of one layer, a proof-print is immediately made visible upon the other layer by exposing the same to a strong light-ray, the 45 film thus requiring no further developing process to produce a visible proof-print.

The character of the invention is not confined to the structures as described and illustrated, but has a more broad application to the art 50 of photography, its application being limited only by the scope of what hereinafter may be claimed.

Referring more particularly to the drawings, the Figure 1 illustrates a transparent or opal base 1 having upon its side 2 a film or negative material 3 or having a coating of negative emul- 55

sion upon the outer side 4, the base 1 having upon its opposite side 5 a coating of printing-out emulsion 6 the back of which is covered by a waterproofing element 7. The Figure 2 illustrates a transparent or opal base 1' having upon its side 5' 5 a film or negative material 3' or having a coating of negative emulsion upon the outer side 4', the base 1' having upon its opposite side 5' printing-out paper 6', the back of which is covered by a waterproofing element 7'. In using opal base, illustrated by the Figures 1 and 2, it has been discovered that, after making the first exposure on the negative emulsion coated side of the film and, while protecting the reverse side of the layers, subject the exposed side to developing and fixing solutions, the printing-out emulsion, by subjecting the exposed side of the layers to a strong actinic light-ray, forms a positive image of the subject already photographed whereby the operator or other individual may 20 see the immediate and positive image of the subject without dissolving the negative layer as shown to be necessary in the previous art. The Figure 3 illustrates a film or negative material 3''' with a coating of negative emulsion at 4''' and 25 printing-out paper 6''' with a plastic layer 4''' therebetween, the back of the printing-out paper having the waterproofing covering 7'''. The Figure 4 illustrates a plastic base 1''' having upon its side 2''' a film or negative material 3''' or 30 having a coating of negative emulsion upon the outer side 4''', the base 1''' having upon its opposite side 5''' printing-out emulsion or paper 6'''. In using the plastic base, illustrated by the Figures 3 and 4, the layers may be pulled apart 35 without ruining either layer and the proof-print thus removed so that duplicate prints may be made from the negative. Of course the well-known method of optical printing system could be used with reflected light and then the proof 40 emulsion would not have to be removed from the layers in making duplicate prints. When the process of developing the negative element is by spraying the negative emulsion coated side of the film the waterproof element may be omitted 45 in the manufacture of the improved film as illustrated by the Figure 4. The Figures 5 and 6 illustrate a negative material 3'''' and printing-out paper 6'''' adapted to be cemented one to the other. The Figure 5 further illustrates the marginal cement layer 4'''' marginally securing the layers 3'''' and 6'''' one to the other along each 50 of the four edges. To provide a close contact between these layers within the uncemented area a vacuum may be established therebetween in 55

any known manner, or the improved film may be placed upon a cylinder during the printing process, the layers 3' and 6' in conforming to the cylindrical surface conforming one to the other in relative close contact. To separate the marginally cemented layers such cemented marginal portions may be cut away, but, if the negative material be in plate form, the layers must be pulled apart. The Figure 6 illustrates two physically distinct bases 3' and 6', one of which is provided with a coating of negative emulsion upon its surface 4' and the other base is printing-out paper or is coated with printing-out emulsion as at 8, the distinct bases 3' and 6' being adapted to be cemented one to the other marginally or otherwise before printing.

In using the improved quick proof process film, the film is first photographically exposed in the usual manner, the side of the film having the coating of negative emulsion having been exposed thereby to the subject the image of which subject is then developed upon the film by the usual developing and fixing process, but when, after such developing, the film is exposed to a strong actinic light-ray by means of which the negative image, as developed upon the film, is printed upon the printing-out paper or emulsion thereby producing a proof print without subjecting the printing-out paper or emulsion to any kind of developing solution. This improved method is especially adapted, but not limited, to be used in portrait work in connection with automatic photographic and developing apparatus so that a photographer, after taking a picture of a subject, may develop and fix the negative and then, by merely subjecting the improved film to a light, be enabled to show the proof within a very few minutes without destroying the negative. The improved method therefore has distinct advantages over methods disclosed by the previous art which shows that the negative is necessarily destroyed before the picture is made. In the portrait field the negatives are more important after seeing the proof; for the negatives are required in making duplicates pictures. Further advantages, other than the saving of time and preserving the negatives, are gained by the use of the improved film by reason of the fact that the subject may almost immediately see the result of his posing before the camera and thus substantially reduce the number of required sittings usually made necessary in order that, when the proofs were ready to be seen, a selection therefrom might be had; for, until my invention

and discovery, the posing subject had no means of knowing the immediate result of a particular sitting, without destroying the negative.

I claim:—

1. An article of manufacture, comprising a substantially transparent base having upon opposite sides thereof negative and printing-out emulsions one of which sides is thus adapted to produce an image thereon only after developing, and the other side being adapted to produce a positive image merely by subjecting the same to a strong light-ray. 5

2. An article of manufacture, comprising a transparent base having upon one side a layer of film material having a coating of negative emulsion, and upon the opposite side a coating of printing-out emulsion exteriorly waterproofed. 10

3. An article of manufacture, comprising a transparent base having upon one side thereof a layer of film material having a coating of negative emulsion, and upon the opposite side thereof printing-out paper exteriorly waterproofed. 15

4. An article of manufacture, comprising two physically distinct bases the face of one of which is provided with a coating of negative emulsion and adapted to be photographically exposed and developed, and the face of the other base being coated with a printing-out emulsion and cemented back to back to said first base so that a positive image may be seen upon it after merely 20 subjecting the same to a light. 25

5. An article of manufacture, comprising two physically distinct bases, the face of the first of which is provided with a coating of negative emulsion, and the face of the second being coated 30 with a printing-out emulsion and marginally cemented back to back to the said first base which, being adapted to be photographically exposed and developed, adapts the second base for producing a positive proof visible thereon after 35 subjecting the same only to a strong light-ray. 40

6. As an improvement in quick proof process films, comprising an opal base having upon one side a layer of film material having a coating of negative emulsion, and upon the opposite side a coating of printing-out emulsion exteriorly waterproofed. 45

7. As an improvement in quick proof process films, comprising an opal base having upon one side thereof a layer of film material having a coating of negative emulsion, and upon the opposite side thereof printing-out paper exteriorly waterproofed. 50
